(57) **CLAIM**

The ornamental design for a carrier substrate for handling as shown and described.

DESCRIPTION

FIG. 1 is a perspective view of a first embodiment of a carrier substrate for handling, showing our new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof;

FIG. 6 is a bottom plan view thereof;

FIG. 7 is an enlarged view taken from encircled portion labeled, "FIG. 7," in FIG. 1;

FIG. 8 is an enlarged view taken from encircled portion labeled, "FIG. 8," in FIG. 1;

FIG. 9 is an enlarged view taken from encircled portion labeled, "FIG. 9," in FIG. 2; and

FIG. 10 is an enlarged view taken from encircled portion labeled, "FIG. 10," in FIG. 4.

FIG. 11 is a perspective view of a second embodiment of a carrier substrate for handling, showing our new design;

FIG. 12 is a front elevational view thereof;

FIG. 13 is a rear elevational view thereof;

FIG. 14 is a left-side elevational view thereof, the right-side elevational view being a mirror image thereof;

FIG. 15 is a top plan view thereof;

(Continued)

FIG. 16 is a bottom plan view thereof; FIG. 17 is an enlarged view taken from encircled portion labeled, "FIG. 17," in FIG. 11; and, FIG. 18 is an enlarged view taken from encircled portion labeled, "FIG. 18," in FIG. 14. The evenly-spaced broken lines depict parts of the carrier substrate for handling that form no part of the claimed design. The dot-dash broken lines depict boundaries of the enlarged portion views shown in FIGS. 1, 2, 4, 7-11, 14, 17, and 18, and form no part of the claimed design.
